Primary Examiner — Wan Laymon

(57) **CLAIM**

The ornamental design for a projector as shown and described.

DESCRIPTION

FIG. 1 is a first perspective view of a projector showing my design;

FIG. 2 is second perspective view thereof;

FIG. 3 is a third perspective view thereof;

FIG. 4 is an elevated front-facing view thereof;

FIG. 5 is an elevated rear-facing view thereof;

FIG. 6 is an enlarged elevated left-facing view thereof;

FIG. 7 is an enlarged elevated right-facing view thereof;

FIG. 8 is a top plan view thereof;

FIG. 9 is a bottom plan view thereof;

FIG. 10 is an enlarged view of area 10 circumscribed in FIG. 1;

FIG. 11 is an enlarged view of area 11 circumscribed in FIG. 2;

FIG. 12 is an enlarged view of area 12 circumscribed in FIG. 2;

FIG. 13 is an enlarged view of area 13 circumscribed in FIG. 4;

FIG. 14 is an enlarged view of area 14 circumscribed in FIG. 4;

FIG. 15 is an enlarged view of area 15 circumscribed in FIG. 5;

FIG. 16 is an enlarged view of area 16 circumscribed in FIG. 5;

FIG. 17 is an enlarged view of area 17 circumscribed in FIG. 8;

FIG. 18 is an enlarged view of area 18 circumscribed in FIG. 8;

FIG. 19 is an enlarged view of area 19 circumscribed in FIG. 9; and,

FIG. 20 is an enlarged view of area 20 circumscribed in FIG. 9.

(Continued)

The broken lines in the drawings depict portions of the projector that form no part of the claimed design.
The oblique shade lines in the drawings show transparency.
